UNITED STATES PATENT OFFICE

171,996

SELF-SERVICE UNIT TO TEST AND STORE ELECTRONIC TUBES

Albert Armato, Whitefish Bay, Wis.

Application September 8, 1953, Serial No. 26,734

Term of patent 14 years

(Cl. D52—1)

To all whom it may concern:

Be it known that I, Albert Armato, a citizen of the United States of America, and a resident of the village of Whitefish Bay, in the county of Milwaukee and State of Wisconsin, have invented a new, original, and ornamental Design for Self Service Unit To Test and Store Electronic Tubes, of which the following is a specification, reference being had to the accompanying drawings, forming a part thereof.

In the drawings:

Fig. 1 is a front perspective view of a self service unit to test and store electronic tubes, showing my new design; and

Fig. 2 is a side elevational view thereof.

I claim:

The ornamental design for a self service unit to test and store electronic tubes, as shown.
